UNITED STATES PATENT OFFICE.

MATHIAS STADTLER, OF SAN JOSE, CALIFORNIA.

UPHOLSTERY-SPRING MOUNTING.

1,254,285.

Specification of Letters Patent. Patented Jan. 22, 1918.

Application filed December 13, 1916. Serial No. 136,648.

To all whom it may concern:

Be it known that I, MATHIAS STADTLER, a citizen of the United States, and a resident of San Jose, county of Santa Clara, 5 State of California, have invented a new and useful Upholstery-Spring Mounting, of which the following is a specification.

My invention relates to a mounting for securing a spiral spring in upholstery.

10 An object of my invention is to provide a mounting for spiral springs in upholstery such that a spring may be easily removed and replaced without disturbing the other springs or the upholstery.

15 The invention possesses other features of advantage, some of which, with the foregoing, will be set forth in the following description of the preferred form of my invention which is illustrated in the drawings.

20 accompanying and forming part of the specification. It is to be understood that I do not limit myself to the showing made by the said drawings and description, as I may adopt variations of the preferred form with- 25 in the scope of my invention as set forth in the claim.

Referring to the drawings:

Figure 1 is a perspective view of the mounting.

30 Fig. 2 is a plan view of the mounting. The direction of the view is from below upward to the under side of the canvas top resting upon the upper end of the spring. The lower portion of the spring is omitted.

35 The mounting of my invention comprises a pocket 5 preferably formed of a leather strip folded lengthwise and stitched to the fabric top 6 in the form of a curve corresponding approximately in form to the 40 curve of the upper turn of the upholstery spring 7. In hard-edge upholstery the pocket 5 may be stitched directly upon the fabric 6, but in spring-edge upholstery I prefer to reinforce the fabric by crossed

tapes 8 in the following manner. I lay out 45 a piece of fabric of the required size and arrange the tapes 8 thereon, spacing them according to the desired spacing of the springs. At each tape intersection I secure a pocket 5 as best shown in Fig. 2, stitching 50 through the folded edges of the pocket, the tapes and the fabric, so that all are tightly fastened together. After preparing the canvas top in this manner, it is inverted over the frame to be upholstered and the 55 springs turned into the pockets one at a time, the lower turn of each coil being sprung into suitably placed hooks 9 which are set in the bottom slats 12 of the frame. When all the springs are in place the edges 60 of the fabric and the ends of the tapes are secured to the frame in the usual manner, and the moss and hair applied.

From the above it will be clear that any one of the springs may be removed without 65 disturbing the others or the upholstery, in case it should be broken or require replacing for any other reason. This is accomplished by springing the lower turn of the coil away from the hooks 9 and turning the 70 spring to disengage the upper portion from the pocket lying on the under side of the canvas top. A new spring is then inserted as first explained.

I claim:

75 An upholstery spring mounting, consisting of a fabric top, crossed tapes arranged upon said top, and a flexible curved pocket adapted to receive the end of the spring and arranged at the intersection of said 80 tapes and secured to said tapes and said fabric top.

In testimony whereof, I have hereunto set my hand at San Jose, California, this 7th day of December, 1916.

MATHIAS STADTLER.

In presence of—

W. ALLEN HOPE.
